CHIME MECHANISM

William George Rex, Sydney, New South Wales,
 Australia, assignor of one-half to Catherine
 Adelaide Rex, Sydney, New South Wales,
 Australia

Application March 20, 1942, Serial No. 435,564
 In Australia February 21, 1941

7 Claims. (Cl. 84—1.04)

This invention has been devised to provide a mechanism for chiming bells or tuned metallic tubes or the like which mechanism may be set to operate automatically to ring the Angelus at predetermined times or which mechanism may be set to operate semi-automatically to ring a bell or tuned metallic tube or the like (a church bell) at regular intervals over a given period of time or which mechanism may be set to ring a carillon of pre-selected chimes. The mechanism includes means to amplify the chimes.

The objects of the invention are attained with mechanical and electrical mechanisms arranged together in combination and comprising:

(a) an electrical switch which for the purpose of ringing the Angelus is a time switch and which for the other functions specified is an ordinary mechanical switch. A circuit with time control means associated with the respective switches. Current supplied per medium of the switch actuates

(b) an amplifying apparatus including a microphone, one or more loud speakers and

(c) an impulsating mechanism to convert current received through (a) into one or a number of impulses at regular or intermittent periods to actuate

(d) a striker mechanism to contact a bell or tuned metallic tube or

(e) a plurality of striker mechanisms to each contact bell or tuned metallic tube and a mechanism to distribute the impulses to the several striker mechanisms.

The invention will be described in detail with reference to the annexed drawings wherein Fig. 1 is a diagrammatic view of the layout of the chiming mechanism; Fig. 2 is an elevation of the time switch and its associated parts; Fig. 3 is a perspective view of the clapper or striking mechanism; Fig. 4 is an elevation thereof partly in section; Fig. 5 is a perspective view of the impulsator utilized when chiming a carillon; Fig. 6 is a cross sectional view thereof; Fig. 7 is a diagrammatic view of the electrical circuit for intermittent as well as continuous chiming; Fig. 8 is a similar view for the chiming of a carillon and Fig. 9 is a diagrammatic illustration of the amplifier employed with the chime.

Referring to Fig. 1, current from the service lead 10 is connected to the time switch 11 by a manually operable switch 12. This time switch is used only in connection with the ringing of the Angelus and is connected electrically by cable 13 to impulsating mechanism located in the casing 14. Impulse currents are conveyed along 55

cable 15 to a rectifier 16 from which the converted current passes along cable 17 to the striker mechanism which includes a magnet 18 adapted to operate the clapper or striker 19. 5 The latter is adapted to impinge against a suspended bell or tuned metallic tube 20. Sound from the tube 20 is received by the microphone 21 and is conveyed electrically by wire 22 to an amplifier 23 and loud speaker 26 from which the amplified sound is emitted. The time switch 11, (see Fig. 2) comprises an electric synchronous clock 28 provided with a twenty-four hour dial 29. The clock actuating mechanism is not shown. Adjustably mounted upon the clock 15 spindle 30 which supports the rotatable dial 29, are three radial arms 31. Any other number of arms may be employed, but three are sufficient for the purpose of illustrating the present invention. Each arm 31 projects beyond the peripheral edge 32 of the dial 29, and each arm 31 is provided with a pair of ratchet teeth 33 and 34 with ramp faces 35 and 36, respectively, over which a pawl 38, on trigger 39, fulcrumed on pin 40, is adapted to ride, said pawl being held in engagement with said teeth by a spring 37. Said trigger 39, when actuated as aforesaid, operates the spring tripping lever 41 in a known manner, and this lever, in turn, operates the cam 43 by contacting the horned plate 42 on 20 said cam 43. This cam 43 is adapted to engage with the contact spring 44, whereby the contact 45 can be opened and closed with a snap action.

Associated with the time switch 11, is a casing 46, in which is contained an electrical circuit 35 having means for controlling the period of operation of the mechanism initially actuated by the time switch. This circuit is depicted in the enclosure shown by the dotted line A in Fig. 7.

Located in the casing 14, is the impulsating 40 mechanism and its accompanying electrical circuit, as depicted in the enclosure shown by the dotted line B in Fig. 7.

Clapper or striking mechanism shown in Figs. 3 and 4, comprises a magnet 18 mounted upon a metal frame 48, on which frame there is provided a pivotally mounted, spring balanced armature 49 which is oscillatable between a pair of oppositely disposed, resilient buffers 50. Each of these buffers 50 may consist of a block of soft rubber which is affixed to a metal disc 51 mounted on the end of an adjustable screw 52. These buffers 50 act as dampers for the armature 49, whereby metallic sounds are prevented from passing into the microphone. Coil spring 53 which is associated with the armature, has an

adjustable tension screw 54. Rigidly secured to the armature 49 at the upper end thereof, is one end of a radial arm 56, to the other end of which is secured a padded ball 57 which is adapted to impinge against the tuned metal tube 20 suspended by means of a card 58 from a suitable supporting hook 59.

In Figs. 5 and 6 is shown the impulsator utilized in conjunction with a carillon chiming mechanism the details of which are depicted in Fig. 8. This impulsator consists of a number of spaced discs 60 of dielectric material, mounted rigidly upon the axle 61, the opposite ends of which are journaled in bearings in the brackets 62. These brackets 62 are mounted upon a base plate 63 of dielectric material. Each disc 60 is provided with a circular row of spaced openings 64 into which pins or pegs 65 are adapted to fit and each row of pins or pegs 65 are adapted to operate one of the group of contact springs 66. The number of discs and contacts coincide with the number of bells or tubes forming the carillon. Each set of contact springs 66 is connected to an independent striking mechanism of the type depicted in Figs. 3 and 4. Axle 61 is driven by worm gearing 67 from an electric motor 68 and said axle 61 is provided with a pair of cams 135 and 136, the latter having a cam lug 137, as shown in Fig. 5. The function of these cams will be hereinafter described.

The impulsating mechanism contained in casting 14 (enclosed by dotted lines B of Fig. 7) consists of three independent motors 70, 71 and 72. Motors 70 and 72 are termed control motors, while the motor 71 is termed the impulse motor. On the axle 73 of motor 70, there are a pair of cams 74 and 75, while on axle 76 of motor 71, there are a pair of cams 77 and 78, the latter having thereon a plurality of equally spaced lugs 79. On axle 80 of motor 72, there are three sets of cams 81, 82 and 83, cam 82 being provided with three short lugs 84 and one long lug 85 and cam 83 being provided with a single lug 86.

In applying the invention to the ringing of the Angelus at requisite hours which, according to custom, are 6 a. m., noon and 6 p. m. daily, the radial arms 31 of the time switch 11 are set on the dial 29 to positions which correspond with such hours. As the dial 29 is rotated clockwise and one of the arms 31 reaches the vertical position, the tooth 33 will engage the pawl 38 of the trigger 39 and said pawl will ride up the ramp 35 thereon. After passing over the top of the tooth 33, the pawl will descend rapidly (being pulled by the spring 37), thereby operating the tripping lever 41 which, in turn, actuates the cam 43 through the horned plate 42, thus closing contact 45. Current then passes from lead 87 (see Fig. 7), along wire 88, through closed contact 45, wire 89, closed contact 90, wire 91, normally closed contact 92, wire 93, motor 72, to lead 94. Motor 72 is set in motion and cam 81 closes contact 95, whereby current from lead 87 passes through closed contact 95, wire 97, to relay 98, to lead 94. Relay 98 is energized and closes contacts 99 and 100, thereby passing current from wire 89, along wire 101, closed contact 99, wire 102, to relay 103, thence to lead 94. Relay 103 becoming energized, closes contact 104 and opens contact 90. The closing of contact 104 allows current from wire 89 to pass through wire 105, through closed contact 104 and through relay 103, whereby said relay is locked up. Simultaneously, current from wire 97 passes through closed contact 100, wires 107 and 93, to motor 72, 75

thereby keeping the latter in motion. Opening of contact 90 breaks the electric circuit through the time switch 11. Cam lug 86 on cam 81, will close contact 108 immediately after the motor 72 is set in motion. Current from lead 87 passes through closed contact 108, wire 110, to relay 111, to lead 94. Relay 111 is now energized and contact 112 is closed, so that current passes from wire 110 through closed contact 112, wire 113, to amplifier 25, whereby the valves in the amplifier 25 become heated before the striking mechanism is set in motion.

After the contact 108 closes, one of the cam lugs 84 on cam 82 will close contact 115, whereby current will pass through closed contact 115, wire 116, to motor 71, to lead 94. This motor 71 is then set in motion, and cam 77 closes contact 117, whereby current from lead 87 passes through the closed contact 117, wires 118 and 116, to the motor 71, which motor will continue in motion until contact 117 is opened. As soon as motor 71 is set in motion, one of the cam lugs on cam 78, 79 will close contact 119 momentarily, whereby an impulse current passes along wire 120 to the rectifier 16. The rectified impulse current passes from the rectifier 16, along wire 121 to magnet 18, to earth. Magnet 18 becoming energized, attracts armature 49, whereby the clapper or striker 19 with its ball 57 impinges against the tube 20 once, whereby a single chime note is produced. This single chime note is received by the microphone 21 and is transmitted through the amplifier 25 to the loud speaker 26. Each time one of the cam lugs 79 closes the contact 119, a single stroke is imparted to the clapper or striker 19.

Each of the cam lugs 84 on cam 82 keep the contact 115 closed for a period of time sufficient to enable the motor 71 to make one complete revolution. During such revolution, the clapper or striker 19 makes three strokes, whereby three single chime notes are given out at the loud speaker 26. As there are three sets of cam lugs 84 adapted to close contact 115, the motor 71 will make three complete revolutions. Consequently, the clapper or striker 19 will make nine strokes, the time period between each set of three strokes being controlled by the spacing of the cam lugs 84. Thus the first part of the Angelus is completed. The remaining portion of the Angelus comprises nine chime notes. Therefore as the cam lug 85 closes the contact 115, such contact 115 will remain closed until the motor 71 has made three complete revolutions, whereby the clapper or striker makes nine successive strokes. Consequently, nine single chime notes are emitted from the loud speaker 26, thereby completing the Angelus. On the opening of contact 95, the current to the motor 72 is automatically cut-off and relay 111 becomes de-energized, thereby rendering the apparatus inoperative. When the pawl 38 of trigger 39 has passed up the ramp 36 of tooth 34 and, passing over said tooth, operates the tripping lever 41 moving it to the position shown by dotted lines thereby actuating the cam 43 to withdraw it from engagement with the contact spring 44, contact 45 is opened and relay 98 is de-energized.

In order to make a continuous succession of chime notes, a push button switch 123 (Fig. 7) is operated in place of the time switch 11, whereupon current from lead 87 passes along wire 124 to motor 70 setting it in motion. Simultaneously, however, current passes from wire 124, to shunt wire 125, to relay 126, to lead 94. Relay 126 be-

coming energized, opens contact 92, whereby the circuit to the motor 72 is broken, thus rendering the Angelus circuit inoperative. Contact 127 is, however, closed, whereby current from lead 87 passes through contact 127, wires 128 and 110, to relay 111, which energizes and closes contact 112, thus enabling current to pass to the amplifier 25 for the purpose of heating the valves therein as before described.

When the motor 70 is set in motion, the cam 75 closes contact 130, whereby current from lead 87 passes through the contact 130 and wire 131 to shunt wire 125, thence to relay 126 which becomes locked up, and current passes also along wire 125 to motor 70, whereby said motor is kept in action after the push button switch 123 has been released. As the motor 70 is set in motion, cam 74 closes contact 132, whereby current from lead 87 passes through the contact 132 to wires 133 and 116, to impulse motor 71, whereupon the latter is thereby set in motion and remains in motion so long as contact 132 is closed. Meanwhile, the cam lugs 79 on cam 78 will close and open the contact 119 in succession, whereby impulse currents are transmitted to the magnet 18. Continuous chime notes are emitted from the loud speaker 26 while the contact 132 remains closed. On opening of such contact 132, the motor 70 and 71 cease to rotate and relays 111 and 126 will thus become de-energized.

To produce a carillon effect, the pins or pegs 65 are arranged in the various circular rows of openings 64 in the discs 60 in a predetermined formation according to the sound effect to be produced. The push-button switch 138 is operated (see Fig. 8) and current from lead 87 passes to motor 68 (Fig. 5), to lead 94, thus setting the motor in operation. Simultaneously, current will pass into relay 126 (Fig. 8), to lead 94. Relay 126 is thus energized and opens contact 92, whereby the Angelus circuit is automatically cut-out, if such Angelus circuit is coupled with the carillon circuit. Contact 140 is closed by cam lug 137 before any other of the contacts are closed. Closing of contact 140 allows current from lead 87 to pass through contact 140 to wires 141 and 110, to relay 111, to lead 94. Relay 111 becoming energized, closes contact 112 enabling the current to pass along wire 113 to amplifier 25 for the heating of the valves therein as before described. Cam 135 now closes contact 143, and relay 126 having been previously energized, contact 144 is closed. Current from lead 87 passes along wire 146, closed contact 144, wire 145, through closed contact 143 to the motor 68, whereby the latter is kept in motion. As the push button switch 138 will be in open position, the relay 126 is locked up.

As the discs 60 are rotated, the pins or pegs 65 will close contacts 148 by contacting with the contact springs 66 in predetermined order. Impulse currents are conveyed through the wires 150 to rectifiers 16 and then to magnets 18, whereby the clappers or strikers 19 are operated.

The individual sounds produced on the metallic tubes 20 are each conveyed to the microphone.

When the motor 68 has made one revolution, the contact 143 opens, whereby the motor 68 stops and relays 111 and 126 become de-energized, whereupon the apparatus is rendered inoperative.

In Fig. 9 of the accompanying drawings, the circuits and apparatus within or comprising the amplifier 25 are diagrammatically illustrated. In this figure, the amplifier is represented as a simple, single stage amplifier employing a simple

triode coupled to the microphone 21 and loud-speaker 26 by means of transformers. It will be understood, however, that the amplifier may comprise any desired number of stages and that any known or conventional form of interstage coupling may be employed. Furthermore, the tube or tubes employed may be of any known or conventional form. In Fig. 9, a conventional power supply for the microphone and amplifier circuits is supplied with energy by way of conductor 113 and relay contacts 112. The voltages for the microphone and tube circuits are derived from the power supply in well known manner.

15 I claim:

1. A chime system comprising electrically operable chime means, control means operatively connected to said chime means for controlling the operation thereof, a microphone positioned to receive sounds emitted by said chime means, an amplifier connected to said microphone and including a vacuum tube having a heating element therein, a sound reproducer connected to said amplifier, supply means for energizing the heating element of said vacuum tube, and means operatively connected to said control means and to said supply means to energize said supply means before and during the operation of said chime means.

20 2. A chime system comprising electrically operable chime means, a source of electrical energy, control means operatively connected to said chime means for controlling the operation thereof and for supplying energy from said source to said chime means at selected times, a microphone positioned to receive sounds emitted by said chime means, a normally deenergized amplifier connected to said microphone and including a vacuum tube having a heating element therein, a sound reproducer connected to said amplifier, and means operatively connected to said control means and to said supply means to energize said supply means before and during the operation of said chime means.

25 3. A chime system comprising electrically operable chime means, means for supplying current impulses to said chime means in predetermined sequence, control means operatively connected to said chime means for controlling the operation thereof and for controlling said impulse supply means, a microphone positioned to receive sounds emitted by said chime means, an amplifier connected to said microphone and including a vacuum tube having a heating element therein, a sound reproducer connected to said amplifier, supply means for energizing the heating element of said vacuum tube, and means operatively connected to said control means and to said supply means to energize said supply means before and during the operation of said chime means.

30 4. A chime system comprising electrically operable chime means, means for supplying current impulses to said chime means in predetermined sequence, timing means for actuating said impulse supply means at predetermined intervals, a microphone positioned to receive sounds emitted by said chime means an amplifier connected to said microphone and including a vacuum tube having a heating element therein, a sound reproducer connected to said amplifier, supply means for energizing the heating element of said vacuum tube, and means operatively connected to said timing means and to said supply means to energize said supply means before and during the operation of said chime means.

5. A chime system comprising electrically operable chime means, control means operable through a cycle for supplying predetermined impulses to said chime means, means for initiating operation of said impulse supply means, a microphone positioned to receive sounds emitted by said chime means, a normally deenergized amplifier connected to said microphone and including a vacuum tube having a heating element therein, a sound reproducer connected to said amplifier, supply means for energizing the heating element of said vacuum tube, and means operatively connected to said control means and to said supply means to energize said supply means before and during the operation of said chime means.

6. In a chime system, an electrically operable chime device, means operable through a cycle for supplying a predetermined succession of impulses to said device, timing means for initiating operation of said first named means at predetermined times, a microphone positioned to receive sounds emitted by said chime device, a normally deenergized amplifier connected to said microphone and including a vacuum tube having a

heating element therein, a sound reproducer connected to said amplifier, supply means for energizing the heating element of said vacuum tube, and means operatively connected to said timing means and to said supply means to energize said supply means before and during the operation of said chime means.

7. In a chime system, a plurality of electrically operable chime devices, means operable through a cycle for supplying impulses in predetermined sequence to said devices, control means for initiating operation of said first named means, a microphone positioned to receive sounds emitted by said chime device, a normally deenergized amplifier connected to said microphone and including a vacuum tube having a heating element therein, a sound reproducer connected to said amplifier, supply means for energizing the heating element of said vacuum tube, and means operatively connected to said control means and to said supply means to energize said supply means before and during the operation of said chime means.

WILLIAM GEORGE REX.
